SAFETY ENVELOPE

Filed Aug. 24, 1926

INVENTOR.

A. W. WALKER,
BY *Frank J. Catherby*

ATTORNEY.

- FIG - 2 -

UNITED STATES PATENT OFFICE.

ARTHUR W. WALKER, OF CONWAY, MISSOURI, ASSIGNOR OF ONE-FOURTH TO CHARLEY N. FINN, OF CONWAY, ARKANSAS.

SAFETY ENVELOPE.

Application filed August 24, 1926. Serial No. 131,201.

My invention, in its broad aspect, has reference to improvements in envelopes; and more particularly it is my purpose to provide an envelope especially adapted to facilitate the transmission of money, both paper money and coin, as well as checks, vouchers, and the like. My envelope is unique in that it cannot be tampered with or opened without leaving evidence that cannot be eradicated, and this major advantage is accomplished without mutilation of the contents. Furthermore, my envelope is simple in construction and can be easily manufactured by ordinary cutting and folding machines at small cost, and there are no metallic parts, fragile extensions, or other undesirable structural elements which would render it unadaptable for general use in the mails.

Other and equally important advantages of my envelope may be briefly defined as follows: first, the entire body and enclosing flaps making up the envelope are formed of a single, one-piece, simple paper form, the enclosing flaps or extensions of which are substantially the same size and shape as the body; second, the currency container is a conventional form of "pay envelope", the flap of which is utilized for my purposes in retaining the container or pocket in the envelope as well as forming a closure for the pocket; third, the folding scheme of my envelope is simple and can be accomplished in a short time by one having no special skill, and fourth, while the envelope itself is mutilated beyond repair in the process of opening (so that it cannot again be sealed up or used over again) there is no way in which the contents of the envelope can be injured during the operation.

The particular elements of my envelope employed to accomplish the above and other equally important objects and advantages will be hereinafter more fully described in detail, and defined in the claims appended hereto and forming part of this specification.

In the accompanying drawings wherein is illustrated the preferred embodiments of my invention:

Figures 1, 2 and 3 are perspective views showing different stages in the process of making up my envelope and inclosing therein its contents.

In the drawings wherein like characters of

reference are used to designate like or similar parts throughout the several views:—

The numeral (1) designates the body or back of my envelope which is shown as rectangular, (2) and (4) are the two side flaps, and (3) and (5) are the two end flaps. Thus the form of the blank from which my envelope is made up resembles substantially a Greek cross, and it may be readily stamped out of paper stock by any one of a number of paper cutting and stamping machines. The side flaps (2) and (4) as well as the end flaps (3) and (5) are substantially the same size and shape as the body (1).

Pasted (or otherwise attached) to the body is a coin pocket or container (6), which resembles an ordinary "pay envelope", the flap (7) thereof being used for purposes of attachment, and when folded down upon the body the pocket (6) is manifestly closed. The flap (2) has formed therein an elongated transverse slot (8) which is disposed midway of its length, and the flaps or extensions (3) and (4) have circular (or otherwise shaped) openings (9) and (10) respectively which are adapted to register with each other and with the slot (8) when the flaps are folded down upon the envelope when it is made up. The flap (5)—shown crinkled in Figure 1—is in its first form made up flat like the other flaps. Flaps (3) and (4) have gummed edges as shown at (11) and (12) respectively.

In making up my envelope, currency, that is, coin, is placed in the pocket (6) which is then folded down upon the body. Paper money, checks and the like are spread out on the body (1) over the pocket (6), and on top of the same is placed a remittance slip or the like, designated (13). The flap (2) is then folded down upon the body and the end (14) of the remittance slip (13) is inserted through the slot (8). Flap (5) is now placed upon its end upon the free end of the remittance slip and the two are folded or rolled up together with the flap (5) on the outside after the manner shown at (15) in Figure 3. Flap (3) is now folded down on flap (5) and pasted thereto with the opening (9) registering with the rolled member (15), whereupon flap (4) is folded down and sealed upon flap (3) with its opening (10) in registry with opening (9), and sealing wax or other sealing substance is run

into and around the openings to firmly hold the flaps (3) and (5) and rolled portion (15) together. Thus, a triple seal is affected; first, by the gummed portions of flaps (3) and (4); second, by the rolled portion (15), and; third, by the sealing wax. To open the envelope a knife is run along the line indicated at the intersection of flaps (3), (4) and (2), and the body (1) to roll (15). The contents can then be counted, but not removed without breaking the seal and tearing out slit (8). The envelope cannot otherwise be effectively opened, and it is manifest that any tampering with it will be immediately evident.

While in the foregoing there has been illustrated and described such combination and arrangement of elements as constitute the preferred embodiment of my invention, it is nevertheless desired to emphasize the fact that interpretation of the invention should only be conclusive when made in the light of the subjoined claims.

Having described my invention and its objects with such attention to detail as will thoroughly acquaint one skilled in the art with its construction and advantages, I claim:

1. An envelope comprising a body, a plurality of flaps or extensions on the body, certain of which have gummed edges, a pocket member attached to the body, the flaps or extensions being folded one above the others upon the body and above the pocket member, one of the said flaps being rolled with the contents of the envelope, and means for sealing certain of the flaps or extensions to each other and to the rolled portion.

2. An envelope comprising a body, an extension or flap on each of the sides of the body and foldable one above the others upon

the body, certain of said flaps or extensions having registering openings, one of said flaps being rolled with a portion of the contents of the envelope, and sealing substance placed in the registering openings and adhering to said rolled portion and the flaps containing the openings whereby to hold said flaps and rolled portion together.

3. An envelope comprising a quadrangular body, a plurality of flaps or extensions integral with the body and arranged on each edge thereof respectively, and foldable upon the body one above the others, certain of the flaps having registering openings, another of the flaps having a slot therein through which a portion of the contents of the envelope is received, another of the flaps being rolled with the contents of the envelope, and sealing substance placed in said registering openings and adhering to the rolled portion and to the flaps having said openings to hold said flaps and rolled portion together.

4. An envelope comprising a rectangular body, a plurality of flaps or extensions on the body and arranged respectively on each edge thereof and foldable upon the body one above the others, a pocket member attached to the body beneath the flaps, certain of the flaps having registering openings, another of the flaps having a slot therein through which a portion of the contents of the envelope is received, another of the flaps forming a rolled portion in conjunction with a portion of said contents, and sealing means placed in said openings and adhering to said rolled portion and to the flaps having the openings to hold said flaps and rolled portion together.

In testimony whereof, I affix my signature hereunto.

ARTHUR W. WALKER.
